(57) **CLAIM**

The ornamental design for a weaving loom for handcrafts, as shown and described.

DESCRIPTION

FIG. 1 is a front elevation view of a weaving loom for handcrafts, showing my new design;

FIG. 2 is a left side elevation view thereof;

FIG. 3 is a top plan view thereof;

FIG. 4 is a bottom plan view thereof;

FIG. 5 is a perspective view thereof; and,

FIG. 6 is a cross-sectional view thereof taken along line 6-6 in FIG. 1.

The rear elevation view is omitted because the rear elevation view is a duplicate of the front view. The right side elevation view is omitted because the right side elevation view is a mirror image of the left side view.
